UNITED STATES PATENT OFFICE.

HOLLAND P. RIDGELY, OF PHILADELPHIA, PENNSYLVANIA, ASSIGNOR TO THE CUTLER ELECTRICAL AND MANUFACTURING COMPANY, OF PHILADELPHIA, PENNSYLVANIA, A CORPORATION OF NEW JERSEY.

SAFETY SWITCH.

Application filed January 2, 1920. Serial No. 348,920.

To all whom it may concern:

Be it known that I, HOLLAND P. RIDGELY, a citizen of the United States, residing in the city and county of Philadelphia, State 5 of Pennsylvania, have invented certain new and useful Improvements in Safety Switches, of which the following is a specification.

My invention relates to safety switches of the character comprising electrical switching 10 mechanism disposed within a housing and operable from the exterior thereof, the housing provided with a movable cover, door or wall permitting access to the interior of the housing, but only when the switching mechanism is in a predetermined position.

My invention resides in safety switch structure of the character hereinafter described wherein the movable housing wall or door is locked in closed position when the 20 switching mechanism is in circuit closing position; the operating means for the switching mechanism is locked against actuation of the switching mechanism to circuit closing position while the housing wall or door 25 is open, and is released for actuation only upon closure of said wall or door and actuation of a detent member by a key member carried by said wall or door; a member for shielding or covering the service terminals 30 of the switching mechanism when said switching mechanism is moved to open circuit position, said member being operatively connected with the door latch; and the door latch is actuated and restrained in pre- 35 determined position by a cam or equivalent member movable with the switch operating handle.

My invention resides in features of construction hereinafter described and claimed.

For an illustration of the preferred of 40 many forms my invention may take, reference is to be had to the accompanying drawings, in which:

Fig. 1 is a plan view of my safety switch 45 in open circuit position with the housing door open.

Fig. 2 is a side elevational view of the structure show in Fig. 1 looking from left toward the right within the housing.

Fig. 3 is a fragmentary side elevational 50 view, similar to Fig. 2, with the door locked closed and the switching mechanism in circuit closing position.

Fig. 4 is a fragmentary sectional view taken on the line A—A of Fig. 2. 55

Fig. 5 is a fragmentary sectional view on the line A—A of Fig. 3.

Fig. 6 is a fragmentary sectional view, on enlarged scale, taken on the line B—B of Fig. 3. 60

Fig. 7 is a fragmentary perspective view of actuating and controlling parts.

Referring to the drawings, 1 is the bottom of the box, of sheet metal or other suitable material, and having the side walls 2 and 3 and the end walls 4 and 5. Hinged to the top edge of the side wall 3 at 6 and 7 is the movable housing wall or door 8.

Secured within the box upon the bottom 1 is the base 9 of slate or other suitable insulating material upon which are secured the stationary switch terminals 10 to which are secured the service or supply cable or conductor terminals 11, the supply conductors or cables, not shown, extending through apertures 12 in the box wall 4. Pivoted at 13 in the standards 14 secured upon the base 1 are the switch blades 15, one for each of the service terminals 10, and adapted to be moved upon their pivots 13 to engage said terminals 10. In electrical communication with each of the switch blades 15 through the standards 14 are the fuse terminals or clips 16 mounted upon the base 1 and with which engage the terminals 17 upon the fuse structures 18, each of which has at its other end a similar terminal 19 engaging in a consumption circuit terminal 20 secured upon the base 1 and in electrical communication with each of which is a terminal 21 of a consumption circuit conductor or cable, not shown, extending through holes 22 in the end wall 5 of the switch housing.

It will readily be understood that when the switch blades 15 are in engagement with the terminals 10, the consumption circuit conductors are brought into electrical communication through the fuses 18 and said switch blades 15 with the supply or service terminals 10. 95

Secured to the ends of the switch blades 15 remote from their pivots 13 is the bar of insulating material 23 by which they are simultaneously actuated. Secured by screws 24 to the bar 23 are the members 25 through 100 pivot holes in which extend the crank or

lever members 26 whose other ends are pivoted in the members 27 upon the switch arm 28 whose one end is pivoted at 29 upon the box wall 3 and at its other end at 30 to the 5 stud shaft 31, which extends through the box wall 2 to the exterior of the box and which is rotatable in the bearing formed by the members 32 held between plates 33, the rivets 34 extending through the plates 33, 10 members 32 and the wall 2 to hold all in place, as indicated in Fig. 6.

Beyond the pivot 30 the switch arm 28 has an extension or arm 35. In the angle between the arms 28 and 35 is disposed the 15 operating lever 36 secured by screws or rivets 37 to the aforesaid stud shaft 31. To the outer end is secured by said screws or rivets 37 or other means the operator's lever 38 having the hand grip 39.

Surrounding the stud 31 is the washer or plate 40 between which and the neighboring plate or washer 33 is disposed the cam or latch actuator member 41 having the lug or projection 42 adjacent which is the recess 43. 20 Disposed in the plane of the cam disk 41 is the latch member 44 pivoted at 45 upon the box wall 2. At its inner end adjacent the cam member 41 the latch member 44 has the arcuate recess 46 of substantially the same radius 25 as the circular periphery of the cam or actuator plate 41, whereby notwithstanding rotation of the cam plate 41 through a considerable angle the latch 44 is prevented 30 from rotating upon its pivot 45, in a manner 35 similar to that characteristic of Geneva stops.

At its other end the latch member 44 has the hook end 47 adapted to enter the opening 48 in the inner end 50 of the rotary key 49 member carried by the door 8.

Pivoted to the box wall 2 at 51 is the 40 detent 52 to whose one end is connected the spring 53 connected at its other end at 54 to the wall 2, the spring 53 being put in 45 to tension by counter-clockwise rotation of the detent 52 about its pivot 51, as viewed from the right of Fig. 7. At its other end the detent lever 52 has the inwardly turned detent or offset 55 having the outward extension 55^a, which latter is actuated by turning key member 49 to rotate member 52 to withdraw detent 55 from position in which it 50 prevents clockwise rotation of latch member 44 as viewed in Fig. 2.

Covering and preventing access to or 55 improper actuation of detent lever 52 when the door 8 is open is the member 57 secured upon the inner surface of the box wall 2 and having in its side 58 the aperture 59, Fig. 1, 60 through which the inner end 50 of the aforesaid key member 49 on the cover 8 may project to engage the detent 55^a of lever 52 to move detent 55 out of the path of travel of the hook end 47 of the latch member 44.

65 Extending upwardly from the bottom 1

adjacent the end wall 4 is the sheet metal plate 60 having the inwardly turned flange 61. Pivoted at 62 in the side walls 2 and 3 are the members 63 to one end of each of which is secured the member 64, as of sheet insulating material, for covering, shielding or rendering inaccessible the service terminals 10 when the switching mechanism is in open circuit position and the door or cover 8 open. At the opposite end 75 of one of the members 63 there is pivoted at 65 the rod 66 pivoted at 67 to the latch member 44, whereby as the latch member 44 partakes of movement upon its pivot 45, the member 64 will be rotated upon the pivot 62.

Pivoted to the box or any other suitable fixed member, as at 68, is one end of a rod 69 connected to one end of the tension spring 70 whose other end coacts with the rod 71 85 pivoted at 72 to the switch arm 28. The pivots 68 and 72 are so disposed that when the switching mechanism is in circuit closing position as indicated in Fig. 3, the spring 70 is in tension with the pivot 30 of the 90 switch arm 28 in line with the pivots 68 and 72 or slightly to the left thereof, in position corresponding with Fig. 3, whereby the structure has attained a position slightly 95 past dead center, whereby the spring 70, notwithstanding its tension, is of itself incapable of opening the switching mechanism.

Upon the exterior of the wall 2 is secured the member 56, Fig. 1, through a hole in which may extend the locking member of a padlock embracing also the operating lever 38, whereby the latter is locked against unauthorized use.

Assuming the switch in open position and the door 8 open, the parts are in the relative 105 positions indicated in Figs. 1 and 2, and the one point, as 46^a, Fig. 2, of the latch member 44 being in the recess 43 of the cam or latch actuating member 41, the latch member 44 being in the position indicated in Fig. 2, wherein the detent 55 prevents clockwise movement of the latch member 44 upon its pivot 45, and the operator's lever 38 is therefore locked in the position indicated, and the member 64 covering the live or supply 110 circuit terminals 10 is also locked.

With the parts in this position any or all of the fuses 18 may be withdrawn or inserted, or blown fuses replaced.

To close the switching mechanism it is 120 first necessary to swing the door to its closed position, and in so doing the end 50 of the key member 49 upon the door 8 enters the slot 59 in the guarding or housing member 57 to position beside extension 55^a on detent 125 55: key 49 is then rotated and its end 50 engages 55^a and so moves detent 55 from in front of hook 47 on member 44 in opposition to spring 53. As the key 49 is rotated 130 as aforesaid to thrust the detent 45 from

position in front of hook end 47 of latch member 44, the offset end 50, of the key member 49, in virtue of the hole 48 therein, rotates over the extreme end of the hook 47, 5 whereby that hook finds itself engaged in the hole 48, and in consequence the door or wall 8 is immediately locked in closed position. The operator's lever 38 may now, since the latch member 44 is itself unlocked, be rotated 10 in a counterclockwise direction, as viewed in Fig. 2, whereupon the lug 43^a, forming the wall of the recess 43 in the cam member 41 opposite the lug or nose 42, also rotating in a counterclockwise direction, engages the 15 point 46^a of the latch member 44, causing that member to rotate in clockwise direction upon its pivot 45, during the earlier stages of the counterclockwise movement of the lever 38 from its position indicated in Fig. 20 2. Accordingly the hook end 47 of the latch member 44 passes further into the opening 48 in the inner end 50 of the key member 49 upon the door or cover 8, into the position shown in Fig. 3, whereby it is impossible, now that the closing movement of the 25 switch mechanism has been begun, to open the door 8.

In so moving to the position indicated in Fig. 3 the latch member has actuated the 30 shield member 64 to bring it to its position indicated in Fig. 3.

Further movement in counterclockwise direction of the operator's lever 38 takes place without further movement of the latch member 44 upon its pivot 45, since its arcuate end 46 now embraces the circular periphery of the cam or latch actuating plate 41 and locks the latch member 44 in the position indicated in Fig. 3. The aforesaid continued 35 movement of the operator's lever 38, however, finally brings the actuating member 36 into engagement with the switch arm 28, forcing the latter to rotate in counterclockwise direction upon its pivots 29, 30, in opposition to spring 70, until the switching mechanism attains circuit closing position with the switch blades 15 in engagement with the service terminals 10, as indicated in Fig. 3.

50 Current will now pass from service terminals through the switching mechanism and the fuses 18 and thence through the consumption circuit terminals to the consumption circuit.

55 With the switching mechanism so in circuit closing position it is impossible to gain access to the interior of the box because the door is locked by the latching member 44.

The circuit may be broken by moving the 60 operator's lever 38 from the position indicated in dotted lines in Fig. 3 in clockwise direction, as viewed in said figure, the first part of the movement of the operator's lever 38 being free until the actuating arm 36, 65 leaving engagement with the switch arm 28,

finally engages the arm 35 of the member 28, finally forcing the member 28 to partake of the similar clockwise rotation. However, after small extent of clockwise movement of the arm 28 the pivot 72 to which the tension spring 70 is attached passes the dead center position, and the spring 70 by its tension, then quickly rotates the arm 28 and the switch blades 15 in clockwise direction, 70 opening the circuit by separating the switch blades 15 from the terminals 10, the arm 28 again catching up with the actuating arm 36, at which time the latch member 44 is still in its position indicated in Fig. 3, holding the door locked in closed position. However, further clockwise movement of the operating lever 38 causes the recess 43 to come to position adjacent the point 46^a upon member 44, and shortly thereafter the nose or lug 42 upon the cam or latch actuator member 41 engages the edge of the latch member 44 adjacent the point 46^a, rotating the member 44 in counterclockwise direction, as viewed in Fig. 3, partially withdrawing the hook end 47 through opening 48 of the key 49 on the door 8, and simultaneously moving the member 64 into position indicated in Fig. 2. The door 8 is still locked closed; it may now be unlocked by rotating key 49 in reverse direction, withdrawing its end 50 from hook end 47, whereupon the door may be swung open upon its hinges 6, 7, and in so doing the end 50 of the key 49 is removed from the path of the extension 55 on the detent lever 52; whereupon the spring 53 contracts and shifts the detent 55 into the position shown in Figs. 2 and 7 in front of the hook end 47 of the latch member 44, thereby holding it in the position indicated in Figs. 2 and 7. The detent 55, acting through the latch member 44 and the cam or latch actuating member 41, locks the operator's lever 38 in the position indicated in Figs. 2 and 7, preventing removal of the shield member 64 and closure of the switching mechanism 100 so long as the door is open.

By the lost motion connection between the actuating member 36 and the switch arms 28 and 35, a quick snap break of the circuit is afforded, with diminished tendency to arcing at the switch contacts, as well understood in the art.

Though my invention is not limited thereto, it will be noted that the pivotal axes of the movable switch element and of the switch actuator are not coincident or concentric, and that the member 26 pivoted to both affords compact structure whereby notwithstanding said eccentricity, the switch actuator may actuate or operate the movable 120 switch elements.

What I claim is:

1. The combination with an electric switch, of a housing therefor having a movable wall, means external to said housing for 130

- actuating said switch, a latch member pivoted within said housing for holding said wall in closed position, said latch operated by said actuating means and in turn locking said actuating means against movement, a movable detent within said housing for holding said latch against actuation, and a member with which said latch engages carried by and rotatable with respect to said wall. 6
2. The combination with an electric switch, of a housing therefor, said housing having a movable wall, a latch within the housing holding said wall in closed position, means external to said housing for actuating said switch and said latch, and a member within said housing movable by said actuating means to and from position for shielding terminals of said switch. 15
3. The combination with an electric switch, of a housing therefor, said housing having a movable wall, a latch within the housing holding said wall in closed position, means external to said housing for actuating said switch and said latch, and a switch terminal shielding member actuated by said latch. 20
4. The combination with an electric switch, of a housing therefor, said housing having a movable wall, a latch within the housing holding said wall in closed position, means external to said housing for actuating said switch and for actuating said latch independently of said switch, and a separate detent member for holding said latch against actuation when said wall is in open position. 25
5. The combination with an electric switch, of a housing therefor, said housing having a movable wall, a latch within the housing holding said wall in closed position, means external to said housing for actuating said switch and for actuating said latch independently of said switch, and a separate detent member biased to position for holding said latch against actuation. 30
6. The combination with an electric switch, of a housing therefor, said housing having a movable wall, a latch within the housing holding said wall in closed position, means external to said housing for actuating said switch and said latch, a detent for holding said latch against actuation and a member movable with said wall for engagement by said latch and for actuating said detent to free said latch. 35
7. The combination with an electric switch, of a housing therefor having a movable wall, means external to said housing for actuating said switch, a latch member pivoted within said housing for holding said wall in closed position, said latch operated by said actuating means and in turn locking said actuating means against movement, a movable detent within said housing for holding said latch against actuation, and a member carried by said wall with which said latch engages, said last named member serving also to actuate said detent to free said latch. 40
8. The combination with an electric switch, of a housing therefor having a movable wall, a latch within said housing for holding said wall in closed position while said switch is in closed position, means operable from the exterior of said housing for actuating said switch, a cam member within said housing rotatable with said actuating means and co-acting with said latch to restrain it against movement, said latch in return when said wall is in open position restraining said cam and thereby preventing actuation of said switch, and a member with which said latch engages carried by and rotatable with respect to said wall. 45
9. The combination with an electric switch, of a housing therefor, said housing having a movable wall, a latch within the housing holding said wall in closed position, means external to said housing for actuating said switch, latch actuating means movable with said actuating means to move said latch independently of said switch to free said wall, a separate detent restraining movement of said latch when said wall is freed therefrom, said latch when held by said detent preventing movement of said switch actuating means. 50
10. The combination with an electric switch, of a housing therefor, said housing having a movable wall, a latch within the housing movable independently of said switch for holding said wall in closed position, switch actuating means having lost motion with respect to said switch, and latch actuating means movable with said switch actuating means for moving said latch to position to lock said wall in closing said switch and to free said wall in opening said switch. 55
11. The combination with an electric switch, of a housing therefor, said housing having a movable wall, a latch within the housing movable independently of said switch for holding said wall in closed position, switch actuating means having lost motion with respect to said switch, latch actuating means movable with said switch actuating means for moving said latch to position to lock said wall in closing said switch and to free said wall in opening said switch, and a spring for snapping said switch open independently of said switch actuating means after initiation of switch opening movement. 60
12. The combination with a pivoted switch member, of a housing enclosing the same, said housing having a movable wall, a pivoted switch actuator, an operating connection between said actuator and said

switch, a latch for holding said wall in closed position, actuating means external to said housing for actuating said switch actuator and said latch, and a member with 5 which said latch engages carried by and rotatable with respect to said wall.

13. The combination with an electric switch, of a housing therefor, said housing having a movable wall, a latch within the 10 housing holding said wall in closed position, means external to said housing for actuating said switch and said latch, a detent for holding said latch against actuation when said wall is in open position, and a key 15 member carried by said wall and rotatable with respect thereto to shift said detent.

14. The combination with an electric switch, of a housing therefor, said housing having a movable wall, a latch within the 20 housing holding said wall in closed position, means external to said housing for actuat-

ing said switch and said latch, a detent for holding said latch against actuation when said wall is in open position, and a key member carried by said wall and rotatable 25 with respect thereto to shift said detent, said key member having an opening in which said latch engages.

15. The combination with an electric switch, of a housing therefor having a movable wall, means external to said housing for actuating said switch, a latch member pivoted within said housing, a member with which said latch is adapted to engage carried by and rotatable with respect to said 30 wall, and a pivoted detent member adapted to move to position between said member and said latch.

In testimony whereof I have hereunto affixed my signature this 31st day of December, 1919.

HOLLAND P. RIDGELY.
